UNITED STATES PATENT OFFICE.

JAMES A. WALTON, OF TAUNTON, MASSACHUSETTS, ASSIGNOR OF ONE-HALF TO FRANK LUTHER ADAMS, OF BOSTON, MASSACHUSETTS.

ROTARY SPINNING-RING AND ADJUSTABLE HOLDER THEREFOR.

No. 921,031.

Specification of Letters Patent. Patented May 11, 1909.

Application filed May 4, 1907, Serial No. 371,865.

To all whom it may concern:

Be it known that I, JAMES A. WALTON, a citizen of the United States, residing at Taunton, in the county of Bristol and State 5 of Massachusetts, have invented certain new and useful Improvements in Rotary Spinning-Rings and Adjustable Holders Therefor, of which the following is a specification.

My invention relates to spinning rings and 10 holders therefor employed in the spinning and twisting of fibers and threads, and particularly to such apparatus in which the rings rotate as the spindles with which they are used revolve.

15 It is now customary to provide holders in special sizes to receive and fit each size ring employed in spinning, that is, a holder of the proper size for each size ring. This adds greatly to the cost of the holders and necessitates the carrying in stock of a large number 20 of holders of each size. Moreover, holders for rotary rings, as heretofore constructed, have no means of adjustment to individual rings. In practice I have found that 25 these rings are not perfectly round, and on account of their warping and shrinking in the process of case-hardening, rings supposed to be of the same size will vary from one to several hundredths of an inch from being true.

30 As these rings must rotate in the holder at a high speed, it will be seen that perfect adjustment of the holder to each individual ring is a necessity in order to secure the highest efficiency.

35 The spinning ring generally used is provided with two flanges, the lower flange resting in the bearings of the holder as the ring rotates, and the upper flange carrying the traveler. In the practical use of such rotary 40 rings, it has been found that, owing to the high speed at which both the ring and the traveler rotate, the lower flange becomes worn by friction with the bearings and the upper flange by friction of the traveler, so the 45 ring soon becomes useless and must be replaced by a new one. These rings are not well balanced, and moreover, lint and dust rapidly accumulate on the traveler and in the bearings.

50 The principal object of my invention is to provide an adjustable holder for rotary spinning rings which will permit the use of as many sizes of rings as possible in one size

holder, and allow for the proper adjustment of the holder to each individual ring.

55

A further object is to improve the construction of rotary spinning rings and provide a reversible ring with a bearing flange intermediate two traveler flanges and adapted to rotate in the bearings of the holder, 60 which ring is, moreover, self-balancing and self-cleaning.

A further object is to improve the construction of the bearing posts which support the rotating ring.

65

These and other objects will more fully appear as I proceed with the description of the invention, of which a preferred embodiment is illustrated in the accompanying drawings, 70 in which—

Figure 1 is a top plan view of my improved holder, with a rotary ring of my improved construction mounted in position; Fig. 2 is a central vertical section taken on the line 2—2 of Fig. 1, and showing the holder mounted upon a ring-rail; Fig. 3 is a detail in cross-section taken on line 3—3 of Fig. 1; Fig. 4 is a plan view of a modification, showing the holder adjustable but without the hinge; Fig. 5 is a side elevation showing a 80 method of locking the arms of the holder in their adjusted position; and Figs. 6 and 6^a are details showing a special construction of the bearing posts.

Referring to the drawings, I have shown 85 the holder as having a base formed of arms A, A¹, upon which are mounted bearing posts B, these latter being provided with bearings, which may be carefully machined slots as shown in Figs. 2 and 4, to receive a 90 flange of the spinning ring. The arms are movable so as to permit of adjusting the bearings to a ring, and in the principal figures are shown as two in number pivoted upon a stud a upon which also is mounted 95 one of the bearing posts. The base is substantially annular in outline and the free ends of the arms preferably overlap and are provided with guiding means consisting of a slot a¹ formed in one of the arms and engaged by a projection a² formed upon the other arm. It will be observed that the slot a¹ is slightly curved, preferably upon a radius having the pivot stud a as a center. The projection a² may be formed by punching and turning up a small portion of the 100

105

metal of the arm. The arms are preferably formed from sheet metal and are suitably bent at a^3 , a^3 , adjacent the points where they overlie one another so that their main portions will lie flat upon the ring-rail.

It is the general custom to attach ring holders to the ring-rail by means of small screws passing through holes in the base of the holders. When several sizes of holders are employed, this necessitates providing several sets of screw holes in the rail. To avoid this difficulty I provide slots in the base of my holder as shown at a^4 , a^5 , which extend preferably at an angle or transversely with respect to the arms of the holder, so that when the arms are moved toward or from each other for the purpose of adjusting the bearing posts for rings of different sizes or to allow for the variation of individual rings, the fastening screws a^6 may still engage the same holes in the ring-rail. These slots a^4 , a^5 are preferably slightly curved upon a radius having the pivot stud a as a center, so that in adjusting the holder it will still remain centered as a whole with respect to the spinning spindle.

The arms or members A, A¹ may be held in their adjusted position by means of the screws a^6 by which they are fastened to the ring-rail, and if desired may be provided also with a set-screw a^7 , as shown in Fig. 5 in place of the simple projection a^2 . Also, the slot a^1 may be open at its outer end, as shown in Fig. 5, instead of closed, as shown in Figs. 1 and 3.

Instead of the solid bearing posts B with their bearing slots b , shown for the purpose of illustration, I may employ a special construction of bearing posts, shown in Figs. 6 and 6^a. Here it will be seen that the post comprises a sheet metal punching C formed up into an inverted U-shape, the ends c being turned outwardly and clamped under lugs b^1 punched out and turned up upon the base member A. The ring may be seated in a bearing formed directly in this sheet metal post, or a bearing block c^2 may be inserted within the post C and provided with a bearing slot b , and clamped in this position by a lug c^3 formed upon the top of the U-shaped post. It will be seen that the base ends c have an extended tongue underlying the lugs b^1 , as indicated by dotted lines.

My improved ring D comprises an upper and a lower traveler flange d , d^1 , each extending across an end of the annular body of the ring. Intermediate these flanges, preferably midway, is a bearing flange d^2 which is shown as flat and of greater width than the traveler flanges. This flange is also slightly thicker than the others, is preferably square at the edge, and engages the bearing slots of posts B. The width of the bearing flange d^2 is such that when the ring is in position 65 the lower flange d^1 will clear the bearing

posts, and the traveler moving around the upper flange d will just clear the top of the posts.

The use of my improved rotary ring and holder is obvious from the drawings and the foregoing description. Rings may be readily removed from and inserted in the holder by loosening or removing screws a^6 and spreading the arms A, A¹. The movement of these arms upon their pivot permits of perfect adjustment to rings of different sizes, and also a fine adjustment to each individual ring which is an absolute necessity for securing the highest efficiency of rotary rings. When the ring D is seated with its bearing flange in the bearings of the posts, if no adjustment were possible to allow for the variations and defects of the individual rings, there would be binding or improper motions of certain rings causing trouble and delay in the entire spinning operation. With a perfect adjustment for the holder to each individual ring, however, this variation in the rings is allowed for.

My novel form of rotary ring, both in itself and in combination with my adjustable holder, has several important advantages. The ring is reversible, so that when one of the traveler flanges is worn by the traveler, the ring may be inverted and the other traveler flange used, thus prolonging the life of the ring. Moreover, the extended bearing flange serves to balance the ring during rotation, causing it to revolve more steadily and thereby producing better yarn. Further, the centrifugal action and draft caused by the rapid rotation of the bearing flange, in addition to that of the other parts of the ring, blows away the fiber and dust from the bearings and prevents the latter from becoming clogged; and the tops of the bearing posts, being in close proximity to the moving traveler, act as traveler cleaners. It will be seen, therefore that the ring is both self-balancing and self-cleaning.

While I have described my holder as consisting of two arms, I do not wish to be understood as limiting the scope of the invention to that number. The holder may be composed of a single continuous strip, so that the arms are connected by a spring portion of the strip instead of by a hinge, this construction being shown in Fig. 4, or the number of arms may be varied without departing from the invention. Although I prefer my improved form of rotary ring, an ordinary ring may be used in my holder as indicated at D¹ in Fig. 5. Also, it is not necessary to pivot the arms at one of the bearing posts, as this pivot may be located elsewhere, as shown in Fig. 6, and the exact position and number of the bearing posts may be varied.

Various other changes and modifications may be made without departing from the

invention, and these I wish it understood fall strictly within the scope thereof.

Having described my invention, what I claim as new, and desire to secure by Letters

5 Patent of the United States, is:—

1. A holder for rotary spinning rings comprising a base formed of adjustable arms connected together, supports uprising at intervals from said base and provided with 10 bearings for a rotary ring, and means for adjusting said arms with respect to each other and thereby fitting said bearings to a ring.

2. A holder for rotary spinning rings comprising members hinged together to allow 15 of adjustment, bearing supports rigidly mounted upon said members and provided with bearings for a rotary ring, and means for clamping said members in an adjusted position.

20 3. A holder for rotary spinning rings comprising a substantially annular base formed of arms hinged together, bearing posts upon said base having bearings for a rotary ring, said arms being movable to effect adjustment of said bearings for rings of different sizes, and means for clamping said arms in an adjusted position.

4. A holder for rotary spinning rings comprising two adjustable members hinged together to form a substantially annular base, the free ends of said members overlapping, means for mounting a ring upon said base, and means for clamping said members.

35 5. A holder for rotary spinning rings comprising two adjustable members hinged together to form a substantially annular base, the free ends of said members overlapping, one of said ends being provided with a slot and the other with a projection moving in 40 said slot when said members are adjusted, and means for mounting a ring upon said base.

6. A holder for rotary spinning rings comprising two adjustable members hinged together to form a substantially annular base, and each formed with a slot for the reception 45 of means for fastening said holder to a ring-rail, said slots being so disposed that said annular holder remains centered when said members are adjusted on said means for rings of different sizes.

50 7. A rotary spinning ring having an upper and a lower traveler flange and a relatively wide bearing flange concentric with the axis of rotation of the ring between said traveler flanges.

8. A reversible rotary spinning ring having an upper and a lower traveler flange and a relatively wide bearing flange concentric with the axis 55 of rotation of the ring centrally located between said traveler flanges and extending outwardly.

60 9. A rotary spinning ring having an upper and a lower traveler flange and a relatively wide heavy bearing flange concentric with

the axis of rotation of the ring intermediate said traveler flanges, which said bearing flange acts to balance the ring during rotation.

10. The combination with a holder comprising a base formed of adjustable arms connected together, supports uprising at intervals from said base and provided with bearings, of a spinning ring rotatably mounted in said bearings, said arms being adjustable 75 with respect to each other to adjust said bearings to said ring.

11. The combination with a holder comprising a base, supports uprising at intervals from said base and provided with bearings, 80 of a spinning ring having a bearing flange in rotative engagement with said bearings and a traveler flange in proximity to said bearing supports, and a traveler movable upon said traveler flange in close proximity to said supports whereby the latter act as cleaners.

12. The combination with a holder comprising a base, supports uprising at intervals from said base and provided with bearings, of a spinning ring having an upper and a 90 lower traveler flange, a bearing flange intermediate said traveler flanges in rotative engagement with said bearings, and a traveler movable upon said upper flange in close proximity to said bearing supports. 95

13. The combination with a holder comprising members hinged together and bearings rigidly mounted upon said members, of a spinning ring rotatably mounted in said bearings, said members being movable with 100 respect to each other upon said hinge to adjust said bearings to said ring.

14. The combination with a holder comprising a base formed of arms, supports uprising at intervals from said base and provided with bearings, of a spinning ring having an upper and a lower traveler flange, and a relatively wide intermediate bearing flange 105 in rotative engagement with said bearings, said arms being movable to adjust said bearings to the bearing flange of said ring. 110

15. The combination with a holder comprising a base formed of arms, bearing posts upon said base having bearing slots, of a spinning ring having an upper and a lower 115 traveler flange, a relatively wide intermediate bearing flange in rotative engagement with said bearing slots, and a traveler movable upon said upper flange in close proximity to said posts, said arms being movable 120 to adjust said bearings to the bearing flange of said ring.

16. A spinning ring holder, comprising two sections, means for pivotally connecting one end of one of the sections to the adjacent 125 end of the other, and means for adjustably connecting the other ends of the sections.

17. A spinning ring holder, comprising separate sections, means for pivotally connecting the sections at one end, and means 130

for adjustably connecting the sections at the other end thereof.

18. A spinning ring holder, comprising a plurality of separate sections, means for pivotally connecting adjacent ends of sections, and means for adjustably connecting the free ends of two sections.

In testimony whereof I have affixed my signature in presence of two witnesses.

JAMES A. WALTON.
